GOLF PUTTER

Karsten Solheim, 10412 N. 37th St., Phoenix, Ariz.

Filed Feb. 20, 1962, Ser. No. 68,901

Term of patent 14 years

(Cl. D34—5)

FIG. 1

FIG. 3

FIG. 1 is a fragmentary rear perspective view of a golf putter showing my new design;

FIG. 2 is a front perspective view; and

FIG. 3 is a sectional view taken on the line 3—3 of FIG. 2.

The balance of the shaft being conventional, same is fragmentarily depicted in broken lines in FIG. 2 for convenience of illustration.

I claim:

The ornamental design for a golf putter, substantially as shown and described.
